[57] CLAIM

The ornamental design for a uv blocking beach umbrella, as shown and described.

DESCRIPTION

FIG. 1 is a perspective view of the uv blocking beach umbrella embodying the design of the present invention;

FIG. 2 is a front elevational view thereof, the rear being a mirror image of the front shown in FIG. 2;

FIG. 3 is a side elevational view thereof, the side opposite being a mirror image of the side shown in FIG. 3.

FIG. 4 is a top plan view thereof;

FIG. 5 is a bottom view thereof; and,

FIG. 6 is a typical elevational view thereof in the closed condition, all elevational views being identical to FIG. 6 when the device is closed.

FIG. 2

FIG. 3
